UNITED STATES PATENT OFFICE.

EDGAR H. FREEMAN, OF TRENTON, NEW JERSEY.

KEY-SOCKET.

1,016,136.

Specification of Letters Patent. Patented Jan. 30, 1912.

Application filed June 10, 1911. Serial No. 632,506.

To all whom it may concern:

Be it known that I, EDGAR H. FREEMAN, a citizen of the United States, residing at Trenton, in the county of Mercer and State of New Jersey, have invented certain new and useful Improvements in Key-Sockets, of which the following is a specification.

This invention relates to the subject of electrical lamp sockets, more particularly to that type of socket known as a key-socket embodying a key-controlled switch-mechanism for making and breaking the circuit through the lamp.

To this end the invention has in view certain novel and practical improvements in that class of key-sockets having a switch body of insulating material which carries the entire switch-mechanism, as well as the separate line wire terminals, and the plug contacts.

A special feature of the invention is to provide a novel construction and arrangement of elements which secures a proper and effective separation of opposite polarity parts, while at the same time so exposing all parts as to render them conveniently and readily accessible for inspection, adjustment or repair. In carrying out this special object, the invention provides a structure which may be utilized with a two-piece switch body of insulating material, and which involves the novel feature of providing such a body with a single external housing chamber for the switch-mechanism and the separate line wire terminals, which housing chamber is entirely open throughout and is only covered by the shell of the external casing when the socket is set up. This feature of improvement admits of easy and ready wiring of the socket, while at the same time exposing every metal part to ready inspection which is of considerable practical importance.

Another object of the invention is to provide a key-socket having strong, compact and good contacts, as well as a positive reliable switch-mechanism having a quick break.

The essential features of the invention are necessarily susceptible to structural change without departing from the spirit or scope thereof, but a preferred and practical embodiment is shown in the accompanying drawings, in which—

Figure 1 is a longitudinal sectional view of an electrical lamp socket constructed in

accordance with the present invention, the outer socket casing being shown in dotted lines. Fig. 2 is a side elevation of the two-piece porcelain socket body showing more plainly the single external housing chamber, and the switch mechanism and line wire terminals therein. Fig. 3 is a sectional view on the line 3—3 of Fig. 2, showing one of the insulating blocks in plan. Fig. 4 is a sectional view on the line 4—4 of Fig. 3. Fig. 5 is a detail in perspective of the combined center plug contact and snapper spring. Fig. 6 is a detail in perspective of the switch contact spring.

Like references designate corresponding parts in the several figures of the drawing.

Preferably, in the practical manufacture of the invention, the socket body is of a two-piece construction, the same consisting of two matching blocks of porcelain or equivalent insulating material. The two blocks of insulating material are respectively designated on the drawings by the numerals 1 and 2, and are detachably held together by the fastening screws 3, or equivalent fastening means, and one of said blocks, namely, the block 2, having fitted to one side thereof the usual screw-shell contact 4 for the lamp plug, said screw-shell contact being held in place by the oppositely arranged fastening screws 5 and 6, the screw 6 also acting as a conductor and having its threaded portion engaging a threaded opening 7 in the foot flange 8 of a line wire terminal plate 9, arranged in one portion of the single external housing chamber 10. The line wire terminal 9 is fitted with the usual binding screw or equivalent element 11 for securing a wire to the said terminal.

As above indicated a distinctive feature of the above invention resides in providing the switch body with a single external housing chamber for the switch mechanism and the line wire terminals. This housing chamber is formed by cut out recesses in opposite edge portions of the insulating blocks 1 and 2. The said chamber may be said to be formed annularly in the two-part switch body and extends partly about the periphery of the body and is of sufficient depth to completely receive therein the separate line wire terminals as well as the switch mechanism. The portions of this external annular housing chamber which receive the separate line wire terminals are substantially diametrically opposite, while the interme-

diate portion of the chamber which lies between the line wire terminals is that portion which receives the switch mechanism. Furthermore, the said housing chamber is entirely open at its outer side so as to expose the entire switch mechanism and the line wire terminals for wiring and inspection, and is only inclosed at its open outer side by the insulating lining of the shell of the 10 socket casing, as shown by the dotted lines in Fig. 1 of the drawings.

The switch mechanism comprises a rotatable switch block 12, a switch contact spring 13, and a combined center plug contact and snapper spring 14. The switch block 12 is of the usual and conventional form, that is, it consists of a substantially rectangular metal block loosely interlocked with the key-shaft 15 so as to have a limited 20 independent rotation thereon, while at the same time be turnable therewith. The said key-shaft 15 is provided with the usual externally arranged finger-key 16, and is journaled in the bearing seats 17 formed in complementary relation in the opposing meeting faces of the two insulating blocks 1 and 2.

The switch contact spring 13 lies within recessed part of the block 1, and is held by a screw 18 to the foot flange 19 of the second line wire terminal plate 20, carrying the binding screw 21 and lying within that part of the housing chamber opposite the line wire terminal 9, as shown in Fig. 4.

The spring 14 is of special and novel 35 form, so as to provide a long and deep spring effect for snapping the switch block 12, as well as a substantial center plug contact for the lamp plug. The said strip 14 is formed from a single strip of spring metal 40 redoubled to provide a long and a short spring arm 22 and 23, respectively. The long spring arm 22 is provided at its free end with an angle part 24 provided with a flat bearing plate 25 that is yieldingly held 45 in contact, laterally, with the rotatable switch block 12. The shorter spring arm 23 is disposed within the center of the screw-shell contact 4 and at the base thereof to form the center plug contact for the socket.

The intermediate or body part 14 of the 50 spring referred to is securely held and braced in position by a bridge-bar 26 extending transversely across the said spring and having its ends detachably seated in the 55 recesses 27 provided in one side of the insulating block 2. The said spring 14 as an entirety is seated within a housing recess 28 which is provided in one side of the insulating block 2, and is in open communication with the main housing chamber 10, herein-before referred to.

I claim,—

1. In an electrical key-socket, a body of insulating material provided with a single external annular housing chamber, and in 65 one face thereof with a housing recess in communication with the chamber, line wire terminals arranged in opposite portions of the chamber, and a switch mechanism lying in an intermediate part of the chamber and 70 including a combined center plug contact and snapper spring seated within said recess.

2. In an electrical key-socket, the body, 75 the line wire terminals, and a switch mechanism comprising a rotatable switch block, a switch spring in the electrical circuit, and a combined center plug contact and snapper spring consisting of a redoubled strip of 80 spring metal.

3. In an electrical key-socket, the body, and the switch mechanism comprising a switch contact spring, a rotatable switch block, and a combined center plug contact and snapper spring consisting of a single 85 strip of spring metal redoubled to provide a long and a short spring arm, the long spring arm having at its free end a flat bearing plate yieldingly engaging the switch block, and fastening means for holding the 90 said redoubled strip in place.

In testimony whereof I hereunto affix my signature in the presence of two witnesses.

EDGAR H. FREEMAN.
